CLOSURE

Robert S. Condon, Rutland, Vt., assignor to Fibre Can Machinery Corporation, Rutland, Vt., a corporation of Vermont

Application August 6, 1940, Serial No. 351,567

1 Claim. (Cl. 229—5.7)

The present invention relates to closures and more specifically to a metal closure particularly adaptable for use with container bodies made of fibrous material.

Closures for such containers usually take two forms; one wherein there is provided a ring or breast of such size that it permits a full opening of the container body; the ring carrying a cap which is removably secured thereon either by a full thread, interrupted thread, or a slip fit. In addition, this type of closure often carries a drumhead or tamper-proof seal which must be broken to permit the emptying of the contents from the container. The other type utilizes a breast provided with a centrally located neck to receive the cap or cover; the opening through the neck being of considerably less size than the opening of the container and the breast forming the closure for that portion of the top of the container between the neck and the periphery of the container.

Heretofore, in the manufacture of closures intended to provide a full opening into a fibre bodied container, it has been customary to telescope the ring or breast over the end of the container body, which, when the removable cap was placed on the ring, resulted in its outer periphery extending well beyond the can body. Because of this construction, when the containers were packed with the closures in abutting relationship, there would be considerable loss of space between two adjacent body members, thus adding considerably to the cost of packing and shipping. In addition, the portion of the closures overhanging the container body gave the contained a top-heavy appearance, which, from a merchandizing point of view, is highly undesirable.

In the second type, the breast was usually seamed to the container body, but to accomplish this it was necessary to depress the breast below its outer peripheral edge to receive the seaming chuck, and thus, when mounted on the body, the top of the container would have a trough between the neck and the peripheral edge thereof. This is highly undesirable in containers wherein if any of the contents is spilled it will collect in the trough, making it difficult to maintain the container clean.

The object of the present invention is to provide a two-piece metal closure for fibre body containers having none of the disadvantages heretofore mentioned.

A still further object is a two-piece closure for

a fibre body container wherein the outer periphery of the cap or cover is substantially flush with the outer wall of the container body.

A still further object is a two-piece metal closure for a fibre body container wherein the ring or breast may be secured to the container body without the use of a seaming chuck or without having to resort to placing of the can body over a horn to accomplish the seaming operation.

10 Other objects will be in part obvious and in part pointed out more in detail hereinafter.

The invention accordingly consists in the features of construction, combination of elements, and arrangement of parts which will be exemplified in the construction hereafter set forth and the scope of the application of which will be indicated in the appended claim.

In the accompanying drawing:

Figure 1 is a view of a completed container partly in section to show the construction of the closure embodying the invention herein;

Fig. 2 is an enlarged fragmentary view showing the ring or breast of the closure in position on the end of the container body just prior to seaming;

Fig. 3 is a view similar to Fig. 2 with the ring or breast seamed to the body; and

Fig. 4 is a view of a completed container partly in section to show the construction of another type of closure embodying the invention herein.

Referring to the drawing, the closure shown in Figs. 1 to 3 comprises a breast or ring 10 of such size that it provides a full opening into the container body 12. The breast 10 has secured therein a drumhead or tamper-proof seal 14 and carries a removable cap 16.

More specifically, the breast 10 comprises an inner ring 18 (see Fig. 3) of considerable depth and having the metal at its lower end reversed or tucked back upon itself through 180° to provide an outer wall 20 to form a double wall thickness having an outer peripheral dimension of such size that it may telescope within the interior of the body 12. As indicated, the outer wall 20 is of less height than the inner wall 18, and extending outwardly from the upper edge thereof is a seaming flange 22 terminating at its outer end in an inturned bead 24.

With this construction, after inserting the ring 10 within the can body, a seaming wheel, diagrammatically shown at 26, is brought into contact with the outer end of the flange 22 to bend or seam it downwardly against the outer surface of the body portion 12 and partially embed the bead 24 into the container body. The

closure ring 10 is thus secured with the end 21 of the body portion enclosed within a V-shaped channel formed by the outer wall 20 of the ring and the down-turned flange 22.

This seaming operation can be carried out without the use of an interior chuck or horn for backing up the seaming wheel, because when the metal is reversed upon itself through 180° at the lower edge thereof there is provided a rim 28 of double the thickness of the metal employed in making the ring. This rim provides an angle iron effect, adding sufficient strength to the otherwise relatively light metal of the body portion to permit seaming without backing up the ring during the seaming operation.

The foregoing construction is particularly advantageous where the ring carries the tamper-proof seal 14. This seal consists of any suitable type of breakable material secured as, for example, by bending over the upper peripheral edge 20 of the body portion 18 of the breast 10 to provide a flange 30 for securely holding the upturned peripheral edge 31 of the drumhead in position. In the manufacture of the closure, this drumhead is secured before the ring is seamed to the container body. It is apparent that the drumhead would prevent the insertion of a chuck to back up the seaming wheel, and, therefore, if the construction shown were not utilized, it would be necessary to place the container over a horn to provide a backing for the seaming wheel. The insertion of such a horn requires extra operations inasmuch as each body would have to be placed over the horn and then removed therefrom; the difficulties of such operations increasing as the length of the container is increased. It will also be noted that with this construction the portion of the inner wall 18 above the plane of the flange 22 provides a throat for receiving the cap member 16, this throat extending beyond the end of the body 12 and lying within the circumference defined by the inner surface of the fibre body 12.

In the embodiment shown, the cap 16 is of usual construction having a top plate 32 and a depending peripheral rim 34. The cap 16 and throat portion of the breast 10 are provided with cooperating interrupted threads 36 for removably securing the cap; it being apparent that any other securing means could be utilized, such as full threads or a friction connection. As the rim 34 of the cap fits closely to the outer surface of the inner wall of the ring and lies above the shoulder 23 formed by the jointure of the ring and body, the entire cap is disposed within the compass of the container body, and no loss of space results in packing. In addition, the container does not appear top-heavy or oversized at one end.

In the embodiment illustrated in Fig. 4, the breast 38 includes a top plate 40 and a centrally arranged neck 42 extending upwardly from the plate 40; the opening through the neck 42 being substantially less than the opening into the container body 44 on which the breast is secured.

In this type of closure, the plate 40 tapers downwardly from the neck and is provided at its outer peripheral edge with a depending inner wall 46, which, as in the first embodiment, is reversed upon itself to provide an outer wall 48 and an extending flange 50 terminating in a bead 52. The outer wall 48 is shown as being of like height to the body portion 46, although it is apparent that the wall 48 need only be of sufficient height to permit a secure gripping of the closure onto the container body as the rim 54 formed by the reversal of the metal will provide sufficient strength to permit the seaming operation. Upon the bending down of the flange 50 to seam the closure into position, the plate 40 will extend to the outer periphery of the body, eliminating the deep trough heretofore found in this type of closure. As indicated, the closure may carry a drumhead 56 and a cap 58, both of which are of like construction to that shown in the prior embodiment.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claim is intended to cover all of the generic and specific features of the invention herein described and all statements of the scope of the invention which, as a matter of language, might be said to fall therebetween.

I claim as my invention:

In combination, a fibre body, a closure for said fibre body including a breast and a removable cover carried by said breast, said breast comprising a one-piece metal ring having an inner cylindrical wall portion of substantially equal uniform diameter throughout its length and an outer wall portion of lesser height than said inner wall portion and formed integral with the lower end of said inner wall portion by reversing the inner wall portion upon itself, a seaming flange extending radially from the upper edge of said outer wall portion, said outer wall portion and the overlapped lower end of said inner wall portion being telescoped within said fibre body with the fibre body abutting the seaming flange, said flange being bent down and secured against the outer surface of said fibre body to secure said breast in position, said inner wall portion of the breast extending above the plane of said seaming flange to provide a cap receiving throat lying substantially within the circumference defined by the inner surface of the body, said cap having a depending peripheral flange closely fitting the outer surface of said throat whereby said cap is substantially flush with the outer surface of the fibre body.

ROBERT S. CONDON.
